UNITED STATES PATENT OFFICE.

LEE LIVINGSTON SCHELLINGER, OF McGRAW, NEW YORK.

RUNNING-BOARD GUARD RAIL FOR FREIGHT CARS.

1,411,938.

Specification of Letters Patent.

Patented Apr. 4, 1922.

Application filed July 26, 1921. Serial No. 487,627.

To all whom it may concern:

Be it known that I, LEE LIVINGSTON SCHELLINGER, a citizen of the United States, and a resident of McGraw, in the county of

5 Cortland and State of New York, have invented certain new and useful Improvements in Running-Board Guard Rails for Freight Cars, of which the following is a specification.

10 My invention is an improvement in running board guard rails for freight cars, and the invention has for its object to provide mechanism of the character specified, for making safe the travel of brakemen and 15 other employees along the running boards of freight cars and to and from the brake wheels.

In the drawings:

Figure 1 is a side view of a freight car 20 having the improved guard rails,

Figure 2 is a top plan view,

Figure 3 is an end view,

Figure 4 is a fragmentary perspective of a car equipped with the invention.

25 In the present embodiment of the invention the freight car body indicated at 1 is supported by the usual trucks 2, and it has the usual running board 3 on its roof. At each end of the car there is the usual brake 30 controlling shaft 4, each shaft having the hand wheel 5 for operating the same.

As is known, on freight trains it is necessary for the brakeman and other employees to travel over the cars when passing from 35 one part of the train to another, and running boards are provided for such travel. These narrow platforms have no protection, and in bad weather movement upon the running boards is exceedingly dangerous. The 40 wind may blow the brakeman off the car especially when he is blinded by driving snow or rain, and in freezing weather ice on the running board increases the danger. Not only is the brakeman liable to slip when 45 traveling but he is liable to be thrown from the car in rounding curves.

In order to provide safety for the employees, I provide a pair of guard rails at each side of the running board. Each pair 50 consists of an upper rail 6 and a lower rail 7, the said rails being connected and supported by posts 8. The posts are arranged in pairs, the members of each pair being on opposite sides of the running board, and 55 each post carries a cross 10 near its lower end

and a T 11 at its upper end. The guard rails 6 and 7 are sectional, and the ends of the sections are engaged with the ends of the crosses and with the ends of the T's.

The brake shafts as in the usual practice 60 are placed laterally with respect to the running boards, and the topmost guard rail of each pair of rails has at that end adjacent to a brake shaft a lateral extension 12. This extension curves downwardly and outwardly 65 as shown in Figures 1 and 2, and it is secured to the topmost hand hold 15 of the side ladder. At the opposite end the guard rail has an extension 13 which curves downwardly to a connection with the running 70 board as shown in Figure 2. The connection between the extension 12 and the handhold is by means of a loop 14 formed on the extension, the said loop engaging the handhold. The posts 8 are secured to the ends of 75 the cross bars which support the running board in any suitable or desired manner. From the moment that the employee reaches the top of the car, he has something to which he may hold. The topmost guard rail is 80 about fifteen inches from the top of the rail, at about the height of the brake wheel. The lowermost guard rail is about three inches higher than the running board which prevents banking of snow, sleet and the like on 85 the guard rail. Since the guard rail is no higher than the brake wheel, it will be evident that the car may run through tunnels, under bridges and the like without interference with the guard rails. In case the 90 brakeman has to approach the edge of the car for any purpose he may easily step over the guard rail.

As illustrated in Figure 4, the lower ends of the standards 8 are provided with elbows 95 to which are connected the ends of cross pipes 8^b. The cross pipes 8^b are in turn extended through flanges 8^a secured to the sides of the running board.

In carrying out the invention the posts 8 100 may be located only at every other feed coupling 10 without sacrificing the necessary strength. Also the cross pipes are not secured to the roof of the car but to the side members of the running board 3 and thereby 105 do not cause leaks in the roof.

A guard rail constructed in accordance with this invention may be applied to tank cars by merely extending a rail (consisting of upper and lower rails) around the outer 110

side or edge of walking platform (or running board on each side of tank) and across ends of tank car frame, a convenient distance from tank.

5 I claim:

1. In a railroad car, the combination with the running board and the brake controlling wheels, of a guard at each side of the running board, said guard at the wheels extending laterally outward to provide a guard for the wheel and for the tops of the side ladders, the guard comprising a series of posts secured to the car and extending upwardly therefrom at each side of the rail, 10 upper and lower guard rails supported by the posts at each side, each of the uppermost guard rails having an extension at each end, one extension curving downwardly and outwardly to a connection with the topmost 15 handhold of the adjacent side ladder.
2. In a railroad car, the combination with the running board and the brake controlling wheels, of a guard at each side of the running board and co-extensive therewith, said 20 guard at the wheels extending laterally outwardly to provide a guard for the wheel and 25

for the topmost handhold of the side ladders, the guard comprising a series of posts secured to the car at each side of the running board and extending upwardly therefrom, 30 and upper and lower guard rails supported by the posts at each side.

3. In a railroad car, the combination with the running board and the brake controlling wheels, of a guard at each side of the running board, said guard at the wheels extending laterally outwardly and downwardly and connected to the topmost handhold of the side ladders to provide a guard for the wheel and for the tops of the side 35 40 ladders.

4. A guard rail assembly for freight cars including a top running board, said running board having side flanges, standards at each side of the running board and spaced apart 45 longitudinally thereof, upper and lower longitudinal rails connected to said standards, and cross rails connecting the lower ends of said standards and extending through the side flanges of the running 50 board.

LEE LIVINGSTON SCHELLINGER.
